UNITED STATES PATENT OFFICE.

FLORENCE I. SAUNDERS, OF EVANSTON, ILLINOIS.

DESIGN FOR A HOLDER FOR FLY PAPER.

Application filed June 27, 1923. Serial No. 6,599. Term of patent 3½ years.

To all whom it may concern:

Be it known that I, FLORENCE I. SAUNDERS, a citizen of the United States, residing at Evanston, in the county of Cook and the State of Illinois, have invented a new, original, and ornamental Design for a Holder for Fly Paper, of which the following is a specification, reference being had to the accompanying drawings, forming a part thereof.

I claim:—

The ornamental design for a holder for fly paper, as shown.

In testimony whereof I have hereunto affixed my signature.

June 20, 1923.

FLORENCE I. SAUNDERS.
